(54) **HULLING CLOVER SEED**

(76) Inventor: **William E. Lukens**

William E. Suckens
Lettered Patent

The Schedule referred to in these Letters Patent and making part of the same containing a description in the words of the said William E. Suckens himself of his improvement in the machine for hulling clover seed.

Be it known that I William E. Suckens of the County of Harrison and State of Ohio have invented a new and useful improvement in a machine for hulling clover seed and that the following is a full and exact description of the construction and operation of the said machine as improved by me. The clover seed huller consists of six parts, viz: 1st frame. 2nd cylinder. 3rd con-
eau. 4th cap. 5th hopper and 6th wind mill. 1st The frame is con-
sisted of 4 posts about 3 feet 3 inches high; 2 rails about 4 feet
long. 3 guides about 3 feet long, exclusive of tenons. Two guides
about 2 inches in thickness and 3 feet 2 inches in length and a
about 1 foot in width which are placed between the rails and the
guides to which the concave is fastened and which is raised and
lowered at pleasure by means of screw bolts; and 4 ties 2 feet 5 inches
long, exclusive of tenons. making a frame the extreme dimensions of
which are 3 feet 7 inches long; 3 feet 2 inches wide and 3 feet high
allowing the timbers to be 3 inches by 3 inches. 2nd The following
is size and construction of a cylinder is presumed to be the best
adapted to the application of a four horse power and congeant
by much be varied according to the power applied. The wooden
heads or live cast rings and one wooden head are snugly wedged
on top of iron of suitable size say 1 $\frac{1}{2}$ inch square on which are
pinched, of wood, and bolted and screwed if iron. as many staves
about an inch and a half thick and 3 feet 8 inches long, as will make
a cylinder about 9 $\frac{1}{4}$ in diameter. On each end of the cylinder is turned
a journal, which rests in metal bearings imbedded in the middle
of the caps of the frame and held down also by metal caps. The cyl-
inder

inder is covered with sheets of cast iron about three eighths of an inch in thickness and of such a width that 5 or 6 pieces will exactly cover the cylinder. The iron is cast in flutes or grooves about one eighth of an inch deep, nearly square on the fore side and sloping on the other the slope extending to the verge of the next flute which makes a sharp edge. These flutes run in a winding direction round the cylinder so as to complete a revolution round it in the distance of 2 feet 6 inches. The remaining two inches, they run in a contrary direction. The object of this is to prevent the sand from crowding in the end of the cylinder. The flutes are about half an inch wide, the cast iron is all fastened by wood screws. On that end of the cylinder shaft to which the power is applied, there is a pulley about 5 inches in diameter which turns by a cord band working on a pulley of half that diameter, a foot farther in the hopper. On same end of the shaft is also hung a balance wheel the size and construction of which will beat the option of the builder. It is preferred however that one 3 feet in diameter weighing 150 lbs will be sufficient. On the other end of the shaft is another pulley of eight inches which turns the sand mill. The concave is made of three stones 2 feet 8 inches long and about 2 inches thick and of such a width, that when put together they will make half a circle. Each end of the middle stone or that one immediately under the cylinder is tenoned so that tenons into the concave concave pieces spoken of in the description of the frame. There are four pieces of wood about 2 inches square and as long as the stones are wide, dressed on the outside and at the ends of the other concave stones. In each of these pieces are placed two seven holes one running through the concave board and the other through the cap. The mortises through which the bolts pass are made sufficiently large to admit of the concave being moved to or from the cylinder at pleasure. The whole forms a concave which reaches to the centre of the cylinder on each side. In the concave are placed sheets of cast iron, the same in thickness of those on the cylinder and are east of the same width of the stones to which

which they are secured by screws. The flutes are the same size and construction of those on the cylinder but run in a contrary direction, that is when the cylinder and concave are in their proper places their flutes cross each other transversely. The flutes run in this direction four fifths of the length of the concave beginning at that end in which the seat is admitted from that to within about an inch of back end. They run lengthwise of the slaves from thence to the end, thus cross those of the cylinder again which completely prevents the seat from crowding in the end of the cylinder and conducts it all to the opening, in the cap through which the seat escapes. The space between the cylinder and concave is from $\frac{1}{8}$ to $\frac{1}{16}$ of an inch at that end to which the power is applied and in which the seat is admitted and from half to an eighth of an inch at the opposite end. $\frac{1}{8}$ The cap is made of as many slaves as may be thought convenient about 20 inches long and about an inch and a half in thickness. These are formed into a concave completely smooth on the inside and of such a size as to cover the cylinder, leaving a space between them of about one fourth of an inch. The sides resting on those of the concave below, this leaves the cylinder bare about a foot from that end to which the power is applied in the admission of the seat and over which the hopper is placed. On that end of the cap next to the hopper, is placed a rib of wood or iron to which the slaves of the cap are firmly secured by screws. The end of this rib project a little below the edges of the cap and are bolted to short ribs which are secured to the outside of the concave slaves which enables the concave to be shifted without moving the cap the other end of the cap is tenoned about half an inch into a plank of suitable thickness and nailed from the outside into the end of the cap slaves. The plank is held to its place by two long bolts reaching through the plank into the cap of the frame. In that side of the cap towards which the top of the cylinder moves on and within $\frac{1}{2}$ of

half an inch of the end of the cylinder there is a mortise ex-
tending 3 inches lengthwise of the cap, and about $3\frac{1}{4}$ inches
crosswise. Through this opening, the seed escapes when rub-
bed. 5th. The hopper is a square box of iron plate half
an inch wider than the diameter of the cylinder and extending
in length from the end of the cap to the end of the cylinder and about $4\frac{1}{2}$
in height. On the top of this there is placed another box about $2\frac{1}{2}$ inches
high, in the shape and form of common hoppers. These two are united by
screws and placed over the vacant end of the cylinder; its side resting on
the concave stand. The foot roller, which is about 3 or 4 inches in diameter
and plated on its surface and placed in the hopper, extending
over the inner side, leaving a space between it and the cylinder of
about half an inch on the outside of the hopper on the shaft. The roller
is a small bullet, turned as above described. 6th. The hairs are
turned by the pinions on the back end of the cylinder shaft, and will
require about double the number of revolutions of the cylinder. The wire
will have a separate frame, and is set under the concave and receives
the seed immediately into the circle as it falls from the roller.

The remainder is constructed and the ridge and screw are taken
in the ordinary method. Operation. The seed after being thrash-
ed off the straw and well raked is thrown into the hopper. The cyl-
inder is put into motion at the rate of 100 revolutions per minute. The
seeds take form of the platen carried the seed under the cap and after
passing several times between the rollers the opening in the cap thro-
ugh it opens and falls into the ridge of the turnabout; the
water-tight portion is thrown off the side and through the ridge
and screw and turned into a box below prepared for its recep-
tion. What I claim as my invention and my improvement is the
peculiar combination and arrangement of the several parts of the before
described machine for cleaning clover seed, but I particularly claim
the method of preventing the seed from crowding in the end of the cylinder
and of conducting it to the place of escape as before described.
